UNITED STATES PATENT OFFICE.

ERNST ENGSTFELD, OF JERSEY CITY, NEW JERSEY.

WINDOW-SHADE FIXTURE.

No. 895,544.

Specification of Letters Patent. Patented Aug. 11, 1908.

Application filed October 22, 1907. Serial No. 398,633.

To all whom it may concern:

Be it known that I, ERNST ENGSTFELD, a citizen of the United States, residing at Jersey City, in the county of Hudson and State of New Jersey, have invented new and useful Improvements in Window-Shade Fixtures, of which the following is a specification.

This invention relates to window shade fixtures.

The object of the invention is to provide an article of this character which may be readily attached to a window casing and be easily detached therefrom without marring or in any way injuring the casing; which shall be capable of a novel and extended range of adjustment, whereby one set of brackets may be utilized for supporting many lengths of shade rollers; and which shall be simple of construction, efficient and durable in use, and cheap and easily manufactured.

With the above and other objects in view, as will appear as the nature of the invention is better understood, the same consists in the novel construction and combination of parts of a shade fixture, as will be fully herein-after described and claimed.

In the accompanying drawings forming a part of this specification and in which like characters of reference indicate corresponding parts, Figure 1 is a view in front elevation of a portion of a window casing showing one of the shade fixtures attached thereto. Fig. 2 is a vertical transverse section through the fixture. Fig. 3 is a perspective detail view of one of the roller brackets.

In illustrating the invention, but one of the fixtures is shown, that on the right-hand side of the window casing, that on the left-hand side being a counterpart, except that the disposition of certain of its parts is transposed.

The fixture embodies a bracket support designated generally 1 and a roller bracket designated generally 2. The bracket support which may be formed of a single piece of metal cast or stamped to the appropriate shape, or constructed of two or more pieces of metal suitably assembled, comprises an attaching plate 3, a rack bar 4 and two terminal stops 5 interposed between the plate 3 and the rack-bar, whereby to provide a guide-way 6. As will be noted by refer-

ence to Fig. 1, the right-hand sides of the teeth are rounded and the left-hand sides are straight, the reason for this arrangement being hereinafter explained, it being understood that the teeth of the right-hand bar are the reverse of that just described.

The roller bracket may be cast or be stamped to shape and comprises the usual arm 7 having an orifice 8 to receive the pintle of the shade roller, a bearing plate 9 disposed at right angles to the arm, a guard 10 and a keeper or dog 11 carried by a lip 12 extending at right angles to the bearing plate 9. The guard is disposed at the lower edge of the bracket and at the point of juncture of the arm and bearing plate, is carried by the latter, and is rearwardly and upwardly bent to embrace the lower upwardly beveled edge 13 of the attaching plate, the coaction between the two parts operating in a positive manner to prevent the loosening of the bracket should the curtain pull string slip from the hand of the operator and thus allow the curtain to wind up violently and without restraint upon its roller. The upper edge of the arm is provided at its point of juncture with the bearing plate 9 with a slot 14 that is designed to straddle the rack bar and thus increase the stability of the assemblage between the parts. The dog 11 is carried by the upper edge of the bearing plate diagonally opposite the guard and is designed to engage with the teeth of the rack bar to hold the bracket at any desired adjustment.

Intermediate of the ends of the bracket support and in its upper outer portion is a depression 15 over which and in the lower edge of the rack-bar is a recess 16, the function of these two parts being to permit assemblage of the bracket with the support. This is effected in the following manner: The dog is passed through the recess to the rear of the rack-bar, the bracket being held at an angle to the face of the supporting plate for this purpose. This will bring the rack-bar into the slot 14 and upon the bracket being moved to the left until the slot will enter the recess, the bearing plate will be moved into contact with the supporting plate, whereupon the dog will engage the rack teeth and the guard the under edge of the supporting plate. The supporting plate is secured to the window casing by screws 17, three in this instance being shown which will permit of the support-

ing plate being readily positioned or removed as required and without injuring the window casing.

When the shade roller is to be hung the 5 pintles are engaged as usual in the bracket orifices and the brackets are adjusted as requisite. Owing to the weight of the curtain, the dogs will be caused to bear against the straight faces of the teeth and thereby be 10 held against shifting while the curved faces of the teeth will permit adjustments when initially positioning the roller.

The improvements herein defined while 15 simple in character will be found thoroughly effective for the purposes defined and will coact in the production of a highly novel and useful attachment.

What I claim is:

1. A window shade fixture comprising an 20 attaching plate provided with terminal stops, a rack-bar spaced from the plate, and a roller bracket having a guard to bear against the attaching plate, and a dog to engage the rack-bar.

25 2. A window shade fixture comprising an attaching plate provided with terminal stops, a rack-bar secured to the stops and spaced from the attaching plate to provide a guide-way, a roller bracket having a bearing 30 plate to engage with the attaching plate and having a guard to engage with the rear side of the attaching plate, and a dog to engage with the rack-bar.

3. A window shade fixture comprising an 35 attaching plate, a rack-bar spaced therefrom to provide a guide-way, a roller bracket provided with a bearing plate to engage with the attaching plate, a guard carried by the bracket and engaging the rear face of the at-

taching plate, a lip projecting from the bearing plate, and a dog carried by the lip to engage with the rack-bar.

4. A window shade fixture comprising an attaching plate, a rack bar carried thereby and spaced therefrom to provide a guide-way, 45 a roller bracket having a bearing plate to project through the guide-way, a dog carried by the bearing plate to engage with the rack-bar, and a guard carried by the bracket to engage with the rear side of the attaching 50 plate.

5. A window shade fixture comprising an attaching plate having its lower edge rearwardly beveled, a rack-bar carried thereby and spaced therefrom to provide a guide-way, 55 a roller bracket provided with an angularly disposed guard to engage the beveled edge of the attaching plate and with a dog to engage the rack-bar, and means for limiting lateral movement of the roller bracket relatively to 60 the attaching plate.

6. A window shade fixture comprising an attaching plate having its lower edge rearwardly beveled, a rack-bar carried by the attaching plate and spaced therefrom to provide a guide-way, a roller bracket having a bearing plate to project through the guide-way, and a slot to straddle the rack-bar, a 65 guard carried by the bracket to engage the beveled edge of the attaching plate, and a dog carried by the bearing plate to engage with the rack-bar.

In testimony whereof, I affix my signature in presence of two witnesses:

ERNST ENGSTFELD.
